UNITED STATES PATENT OFFICE.

GEOEGE JORDAN, OF CHILLIWACK, BRITISH COLUMBIA, CANADA.

LIFE-SAVING DEVICE.

Application filed February 18, 1925. Serial No. 10,024.

This invention relates to an improved life saving device of the kind adapted to be employed by persons trapped in a burning building.

More specifically, the invention relates to a carrier constructed to form a seat for the occupant, said carrier being suspended from an automatically operable braking device connected through the medium of webbing 10 or the like to a suspension hook.

The features and advantages derived from the particular construction and arrangement of parts employed will become apparent from the following description and drawing.

In the accompanying drawings forming a part of this application and in which like numerals are employed to designate like parts throughout the same:

Figure 1 is a side elevation of a life saving device constructed in accordance with the present invention.

Fig. 2 is an enlarged vertical detail section through the improved brake device.

Fig. 3 is an elevational view of the brake device.

Fig. 4 is a fragmentary detail perspective of a portion of the friction band or webbing employed.

Referring to the drawings in detail, it will be seen that the reference character 1 designates a hook which is adapted to take over a relatively stationary part of the building. Carried by and formed integral with this hook is a loop 2 into which one end of a flexible friction band or tape 3 is fastened. This tape extends downwardly and is trained over a plurality of friction bars 4 fixedly mounted between the side plate 5 and a substantially U-shaped member 6. These bars are arranged in predetermined spaced relation to produce the most efficient braking action according to the weight of the individual to be carried. In this connection I would state that the device has been devised with a view of rendering it exceedingly compact so that each person may have his own device.

From experience I have found that with the use of approximately four friction bars arranged in relation as shown with the tapes trained thereover as also shown, the device will operate most efficiently for persons weighing less than two hundred pounds.

For persons weighing comparatively less, a lesser number of bars (preferably three) may be employed. In all instances, how-

ever, the bars will be arranged between the relatively wide plate-like portions 5 of the U-shaped member, thus spacing the lowermost bar upwardly but adjacent the bight 60 portion 7 of the member to accommodate a carrier frame 8.

In the present instance the flexible carrier is somewhat triangular in formation and is provided at its top with a loop-like connector 9 connected to the bight portion 7. The carrier is preferably equipped with a strap or its equivalent 10 to encircle the body of the occupant to guard against accidental displacement. The carrier may be 65 of a width to provide a comfortable self-shaping seat for the occupant who must sit therein. The free end portion of the tape 3 hangs downwardly adjacent the frame so that it can be grasped by the occupant. 70 The tape is preferably of a heavy durable webbing as illustrated in Fig. 4 to guard against undue wear and to produce intense friction. 75

In practice the bill of the hook 1 is engaged with a window stool or its equivalent and the contrivance is hung upon the stool on the outside of the building. Of course, the hook may be engaged with any other appropriate form of support. 80

Holding the free end portion of the friction band, the occupant places himself in the carrier frame in a sitting posture, by letting up on the band, the weight of the occupant causes the same to slide about the friction 85 bars 4 in an obvious manner, permitting slow descension of the same with consequent lowering of the occupant to a point of safety. The operator can manipulate the friction band in a manner to accurately 90 regulate the speed of travel of the same.

It is thought that the foregoing description when taken in connection with the accompanying drawing will enable persons skilled in the art to which this invention relates to obtain a clear understanding of the same and for this reason a more lengthy description is thought unnecessary. 100

Although I have shown and described the preferred embodiment of the invention it is 105 to be understood that minor changes coming within the field of invention claimed may be resorted to if desired.

While I have expressly intimated that the device is restricted more or less to use as 110 a fire escape, I would direct attention to the fact that it may be advantageously used for

other purposes, such as upon boats for enabling the transfer of passengers from one boat to another on a lower elevation.

Having thus described my invention, 5 what I claim as new is:—

In a life saving device of the class described, in combination, a suspension hook adapted to be engaged with a relatively stationary support, a flexible friction tape 10 connected at its upper end to said hook, a braking device adapted for sliding movement upon the intermediate portion of said tape, said device comprising a substantially U-shaped member, the side portions 15 of which are widened considerably at their free ends to provide bar supporting plates, a plurality of friction bars fixedly mounted between said plates, there being four bars, all of which are cylindrical in cross 20 section and disposed in horizontal planes, two of said bars being disposed at verti-

cally spaced superposed points at the central portions of the plates, the remaining two bars being located opposite each other and on a plane between said first-named bars, the 25 free end portion of the tape being reeved beneath the lowermost one of the superposed bars, being passed over the upper one of said superposed bars, being then directed downwardly and around the first-named 30 bar again, over one of the two remaining bars, then beneath the first-named bar again and finally over the remaining one of the said remaining two bars in a manner to cause several plies of the stretches to lie 35 in frictional contact with each other beneath the first-named bar, and a carrier-seat attached to the bight portion of said U-shaped member.

In testimony whereof I affix my signature.

GEORGE JORDAN.
